UNITED STATES PATENT OFFICE.

SAMUEL T. GLASFORD, OF DANVERS, ILLINOIS.

CRUTCH.

No. 928,352.

Specification of Letters Patent.

Patented June 1, 1908.

Application filed July 31, 1908. Serial No. 446,362.

To all whom it may concern:

Be it known that I, SAMUEL T. GLASFORD, a citizen of the United States, residing at Danvers, in the county of McLean and State of Illinois, have invented certain new and useful Improvements in Crutches, of which the following is a specification.

The present invention relates to certain new and useful improvements in crutches and more particularly to a device of this character embodying a novel construction whereby it can be readily adjusted to suit the requirements or peculiarities of any person desiring to use the same. More specifically, the crutch embodying the present invention comprises a body portion having the saddle adjustably connected thereto so that the distance between the saddle and the handle may be adjusted to correspond to the length of the arm of the person, the body portion also having novel adjustable means for connecting a leg to the lower portion thereof so that the length of the crutch can be varied.

For a full understanding of the invention and the merits thereof and also to acquire a knowledge of the details of construction and the means for effecting the result, reference is to be had to the following description and accompanying drawings, in which:

Figure 1 is a side elevation of a crutch constructed in accordance with the invention, portions being shown in section. Fig. 2 is an enlarged detail view of the leg at the lower end of the crutch. Fig. 3 is a horizontal sectional view on the line 3-3 of Fig. 1.

Corresponding and like parts are referred to in the following description and indicated in all the views of the drawings by the same reference characters.

Referring to the drawing, the numerals 1 designate the side pieces of the crutch, the said side pieces being connected at an intermediate point by the handle 2 and the portions of the side pieces below the handle converging toward each other and having their extremities received within sockets 3 upon opposite sides of a sleeve 4. This sleeve has a square or angular cross section and slidably mounted within the sleeve is a leg 5 the lower end of which may be provided with the usual shoe 6. The body portion of the leg is formed with a series of transverse openings 7 any selected one of which is designed to be engaged by a pin 8

passing transversely through the sleeve 4. In this manner the leg may be projected outwardly to lengthen the crutch or retracted to shorten the crutch and then locked in any desired position by passing the pin 8 through the required one of the openings 7.

Threaded within the upper end of the leg 5 is a set screw 9 which passes through slots in arms 10 which engage the side pieces 1 of the crutch to prevent lateral swinging movement of the leg. In the present instance these arms 10 are shown as provided at their extremities with eyes 10^a loosely receiving the side pieces, and the two arms 10 may be moved outwardly or drawn inwardly to accommodate themselves to the downwardly converging lower ends of the side pieces as the leg is moved up and down. It will thus be obvious that the length of the crutch may be adjusted as required by passing the pin 8 through a selected one of the openings 7 and that the arms 10 will operate after the set screw 9 has been tightened to brace the leg and prevent lateral movement of the upper end thereof.

A saddle 11 is formed with the downwardly projecting extensions 12 which have a telescopic connection with the side pieces 1 to admit of the saddle being moved up and down for the purpose of varying the distance between the saddle and the handle 2. As shown on the drawing the upper ends of the side pieces 1 have a tubular formation to receive the extensions 12 and are provided with the set screws 13 for engaging the extensions and locking the saddle in an adjusted position. With a crutch constructed as above set forth it will be obvious that the saddle can be moved up and down to regulate the distance between the saddle and the handle according to the length of the arm of the person desiring to use the crutch, and the length of the crutch itself may be adjusted through the medium of the leg 5.

Having thus described the invention, what is claimed as new is:

1. A crutch comprising a body portion formed with side pieces, a leg slidably mounted between the side pieces and adapted to be raised and lowered with respect thereto, means for locking the leg in an adjusted position, and lateral arms carried by the upper end of the leg and movable in and out upon the same, the said lateral arms having a sliding connection with the side pieces.

2. A crutch comprising a body portion formed with side pieces, a leg slidably mounted between the side pieces and movable up and down with respect thereof, 5 means for locking the leg in an adjusted position, and lateral arms carried by the upper end of the leg and having a pin and slot connection therewith so as to be moved in and out, the said lateral arms having a 10 sliding connection with the side pieces.
3. A crutch comprising a body portion formed with side pieces the lower ends of which converge toward each other, a sleeve being located at the lower end of these side 15 pieces and the sleeve being formed with

sockets receiving the extremities of the side pieces, a leg slidably mounted within the sleeve, means for locking the leg in an adjusted position, and lateral arms carried by the upper end of the leg and movable in and out with respect thereto, the said lateral arms having a sliding connection with the converging lower ends of the side pieces. 20

In testimony whereof I affix my signature in presence of two witnesses.
